UNITED STATES PATENT OFFICE.

ARTHUR J. BAZELEY, OF CLEVELAND, OHIO, ASSIGNOR TO NATIONAL MALLEABLE AND STEEL CASTINGS COMPANY, OF CLEVELAND, OHIO, A CORPORATION OF OHIO.

CAR COUPLER.

Application filed July 7, 1925, Serial No. 41,968. Renewed November 2, 1927.

- Fig. 1 is a side elevation of the lock and thrower embodying my invention; Fig. 2 is a rear elevation of the lock indicating the surface which has a bearing on the thrower; 5 and Fig. 3 is a partial section on line III—III of Fig. 1, indicating the thrower in plan and the engagement, diagrammatically, of the thrower by the lock leg during the knuckle opening movement.
- 10 My invention relates to car couplers and in particular to the A. R. A. standard D-coupler, in which there is frequent difficulty in knuckle throwing because the leverage applied by the lock to the knuckle throwing arm is not arranged for the most effective application of force. My invention, which 15 in its application to the D-coupler involves a redesign of the lock and thrower, eliminates this difficulty of operation by providing much more favorable leverages than are now obtained in the D-coupler, with the result that the knuckle may be thrown without undue effort. My invention also comprises various features which I shall hereinafter 20 describe and claim.
- Referring to the drawings, the coupler head A contains the usual knuckle B and lifter C. The lock D and opener E alone 25 are of altered construction. The top of the lock is cut down toward the rear side of the head, the dotted lines indicating the present shape of the D-coupler lock, to give room for an added lift to the lock and a consequent greater rotation about the fulcrum point 2, and a greater rearward movement 30 of the leg 3 of the lock, with a consequent greater impulse to the knuckle thrower. In the D-coupler the rear side of the lock leg at the beginning of the knuckle throwing 35 movement has practically a horizontal line bearing against the short arm of the knuckle thrower. In the present construction the face 4 of the arm 5 of the thrower, beginning 40 at its point 6 furthest away from the pivot 7, is tapered away from the rear face 8 of the lock leg so as to ensure the engagement 45 of the arm 5 of the thrower by the lock face 8 as far away from the pivot 7 as possible, and thereby increases the leverage of the 50 lock upon the thrower to the maximum extent. The lock face 8 is cut away at 10 so as to prevent contact between that portion of the lock and the arm 5 of the thrower, as such contact would during the latter part of the throwing decrease the effective length of the lever arm 6—7, and thus diminish the impulse transmitted to the thrower. As is shown in Fig. 3, at the beginning of the throwing operation the surface 8 is in contact with the thrower 55 arm at the point a. As the operation proceeds the locus of the point of contact is shown by the dotted lines a, b, c, the effective length of the short arm of the thrower at any point being the distance, perpendicular with respect to the direction of motion of the lock leg, between the contact point and the axis of the thrower trunnion 7. In Fig. 2 the line a', b', c' indicates the movement of the locus of the point of contact of the knuckle thrower on the lock during the knuckle throwing movement. The center line 7^a through the knuckle thrower is also shown in projection in Fig. 2, to indicate the effective length of the lever arm. 60
- As the locus of the point of contact approaches at c' the edge of the surface 8, as is shown in Fig. 2, this surface has been built downwardly as at 11 to provide a sufficient overlap to prevent disengagement between the surface 8 and the arm 5 of the thrower during the knuckle opening movement. 65
- It will thus be seen that the variation in length of the lever arm between the point 70 of contact with the lock and the axis of the thrower is reduced to a minimum, and that the effective length of such arm as compared with that of the D-coupler is greatly increased and maintained during all operations of the lock and thrower. 75
- Locks and throwers embodying my invention can be used in the D-coupler without change in the other parts thereof. Careful tests of D-couplers equipped with locks and throwers of standard form and then with locks and throwers embodying the present invention show that in the latter case approximately 22% less effort was required to throw the knuckle. 80
- Obviously, my invention is applicable to either the top or bottom operated form of the D-coupler. 85
- The terms and expressions which I have employed are used as terms of description and not of limitation, and I have no intention, in the use of such terms and expressions, of excluding any mechanical equivalents of the features shown and described, or portions thereof, but recognize that vari- 90
- 100
- 105

ous structural modifications are possible within the scope of the invention claimed.

What I claim is:

1. In a coupler of the standard D-type, a lock; a two-armed knuckle thrower pivoted in the coupler head, the lock having a rear surface arranged to engage a face on one arm of the thrower in knuckle opening, the said lock surface and said arm face being angularly disposed with reference to each other at the beginning of the knuckle opening movement to prevent excessive shortening of the effective length of the thrower arm during such movement.
2. In a coupler of the standard D-type, a lock; a two-armed knuckle thrower pivoted in the coupler head, the lock having a rear face arranged to engage one of the arms of the thrower, the said face being recessed to limit the lateral extent of its engagement with said arm.
3. In a coupler of the standard D-type, a lock; a two-armed knuckle thrower pivoted in the coupler head, the lock having a rear surface arranged to engage a face on one of the arms of the thrower, the lock surface being recessed to limit the extent of its lateral engagement with said arm, the face of the said arm being arranged to cause the arm to engage the lock surface at the furthest possible distance from said pivot.
4. In a coupler of the standard D-type, a lock; a two-armed knuckle thrower pivoted in the coupler head, the lock having a rear surface arranged to engage a face on one of the arms of the thrower, the arm face being arranged to engage the lock surface at the furthest possible distance from said pivot; and means for limiting the shortening of the effective length of said thrower arm during the knuckle throwing movement.

ARTHUR J. BAZELEY.
